SEWING MACHINE

Harold J. Le Vesconte, Glendale, Calif., and Albert M. Schweda and Clarence C. Smith, Chicago, Ill., assignors to Union Special Machine Company, Chicago, Ill., a corporation of Illinois

Application August 9, 1945, Serial No. 609,766

14 Claims. (Cl. 112—214)

1

This invention relates to sewing machines and, more particularly, to sewing machines embodying a new and improved type of work feeding mechanism for feeding material past the stitch-forming instrumentalities of the sewing machine. It is particularly concerned with a new and improved presser foot and feed roller arrangement and means for driving the roller, which facilitates proper advance of the work under all conditions.

The invention is especially directed to a new and improved material feeding mechanism which is particularly adapted for use on machines intended for sewing heavy materials, or hard fabrics which are difficult to feed, or for the performance of operations in which it is important that the ends of the two plies forming a seam come out even. It also relates to certain associated mechanisms of a new and improved type employed in conjunction with the feeding mechanism and related stitch-forming instrumentalities, such as the presser foot and mechanism for regulating the length of the stitch.

The uniform feeding of heavy or hard materials over the work supports of sewing machines has always been difficult, and such feeding is especially difficult in operations in which the material must be sewn or seamed in such a way that there is no extension of one ply beyond the other at the end of a seam. Feeding mechanisms now available are of such type that heavy or hard materials being fed tend to slip, thus resulting in bunching, crooked seams, and other defects. In accordance with this invention, an upper feed roller is provided and arranged to rotate intermittently in synchronous cooperation with a feed dog of the four motion type in moving the fabric relative to the stitch-forming instrumentalities of the sewing machine.

It is one of the objects of this invention to provide a work feeding mechanism for sewing machines which mechanism is simple and compact, of light weight and capable of high speed, vibration-less operation. It is also an object to provide such a feeding mechanism which is particularly satisfactory for advancing heavy materials, and others which are difficult to feed, past the stitch-forming instrumentalities of the machine.

It is another object of this invention to provide a feeding mechanism of the character indicated, which is positive and accurate in its operation and which is so positioned and arranged in relation to the presser foot and stitching mechanism as to facilitate movement of the feeding mechanism as well as the presser foot in com-

pensation for variations in the thickness of the fabric being fed under the presser foot.

It is still another object of this invention to provide simple and readily accessible micrometer adjustment means, in association with the feeding mechanism, whereby the length of stitch formed by the stitch-forming devices may be varied.

A further object of this invention involves the provision of a spring clutch mechanism of simple yet efficient construction in direct association with a feed roller for driving the feed roller. This mechanism is positive and reliable in its action. Toward this end the spring of the clutch is preferably tapered so that it is relatively flexible at its driving end, but very sturdy at its driven end.

Still another object of this invention has been to provide, in combination with the foregoing feed mechanism, an improved presser foot so mounted and arranged as to provide contact with the fabric in the region of the needle openings, regardless of the extent of its rocking due to the passage of seams beneath the presser foot.

Further objects of this invention include the provision of a direct driving connection between the main drive shaft of the sewing machine and the feed roller, which driving connection is simple and reliable in its operation at all times, and the provision, in combination with this form of driving connection, of simple and effective means for preventing rotation of the feed roller in the reverse direction. This simple and reliable driving mechanism and means for preventing retrograde rotation of the feed roller, are provided in combination with the above mentioned tapered spring clutch which is positioned within the feed roller. By this combination of features a greatly improved feeding action has been produced.

The foregoing objects, features, and advantages 40 of the invention, as well as others which will be hereinafter set forth, may be more fully appreciated by reference to the ensuing disclosure of certain preferred embodiments thereof, keeping in mind that these are intended to be illustrative 45 and not restrictive. The invention may be readily understood from the detailed description which will now be given in connection with the annexed drawings wherein:

Figure 1 is a front elevation of a sewing machine to which the invention has been applied, portions thereof being broken away, and certain parts being shown in section, for clearness of illustration;

Figure 2 is a top plan view of the sewing machine, certain cover plates and other parts be-

ing removed or broken away, and some parts being shown in section, in order to illustrate the construction more clearly;

Figure 3 is an elevational view of the needle head portion of the sewing machine, this view also showing one end of the work supporting arm;

Figure 4 is a fragmentary view, partly in elevation and partly in vertical section, showing the needle head portion of the machine and the arrangement of certain parts associated therewith;

Figure 5 is a view, partly in elevation and partly in vertical section, through the needle head portion and the cooperating end portion of the work-supporting arm, showing the presser foot, feed roller, and associated mechanism;

Figure 6 is a side elevational view of the presser foot and the parts immediately associated therewith;

Figure 7 is a top plan view of the presser foot, feed roller, and parts immediately associated therewith, the presser bar and the vertical rock shaft for intermittently rotating the feed roller being shown in section.

Figure 8 is a cross-sectional view of the feed roller, together with a partial sectional and partial elevational view of the clutch spring by which the roller is rotated, and shows also the driving lever therefor;

Figure 9 is a detail view, in elevation, of the tapered clutch spring;

Figure 11 is an end view of the clutch spring at its driven end;

Figure 12 is a side or edge view of the driving lever for driving the tapered clutch spring;

Figure 13 is a face view of the driving lever;

Figure 14 is a detail view of the feed roller showing the ball means by which the feed roller is held against reverse rotation during the return movement of the driving lever;

Figure 15 is a detail face view of the horizontal link by which the feed roller is driven from the vertical rock shaft;

Figure 16 is a side elevational view of a modified arrangement of the feed roller and presser foot and associated parts, some parts being broken away or shown in section in order to illustrate the arrangement more clearly;

Figure 17 is a horizontal cross-sectional view of the modified feed roller and presser foot construction shown in Figure 16, taken on the line 17-17 of Figure 16, some parts being removed for clearness of illustration; and

Figure 18 is an end elevational view of the modified feed roller and the lower portion of the presser bar, the presser foot supporting frame being shown in cross-section.

For purposes of illustration the invention has been shown as applied to a feed-off-the-arm sewing machine of the type disclosed in Christensen et al. Patent No. 1,741,095, granted December 24, 1929. Reference may be made to that patent for a fuller disclosure of certain features of construction and operation, not essential to an understanding of this invention, which are set forth in detail therein. Certain other features of operation and construction, not disclosed in detail herein, will be found in the Christensen Patent No. 2,372,175, granted March 27, 1945. For a fuller disclosure of the oil pumping system and mechanism associated therewith for conveying lubrication from sumps to reservoirs positioned in the frame of the sewing machine, and for supplying lubricant to the operating parts, reference

should be made to the copending patent applications of Clarence C. Smith, Ser. No. 541,902, filed June 24, 1944, now Patent No. 2,430,370, November 4, 1947, and George Sauer, Ser. No. 561,182, filed October 31, 1944, now Patent No. 2,446,306, August 3, 1948.

Referring to the drawings, the sewing machine may be provided with a frame 11 which may be constructed as shown in the Christensen et al. Patent No. 1,741,095. This frame includes downwardly extending hollow portion 12 and work-supporting arm 13. Power is supplied to the machine through a combined hand wheel and pulley 14, secured to a main drive shaft 15 extending longitudinally of the upper portion of the frame and supported in bearings 16, 17, and 18. The two main sections of the shaft are connected by a coupling 18a. The power delivered may be supplied by an electric transmitter (not shown), including an electric motor, an associated clutch, and other necessary mechanism. It may be of any known construction such as that shown, for example, in the copending application of LeVesconte and Schweda, Ser. No. 449,196, filed June 30, 1942, now Patent No. 2,390,220, December 4, 1945, which construction is also illustrated in said copending application of Clarence C. Smith.

Adjacent the inner end of the main drive shaft 15 there is secured an eccentric 19 which cooperates with the strap portion of pitman 20. At its lower end (not shown) this pitman is connected in a suitable manner with a feed bar 21 (Fig. 5). This feed bar 21 is in turn connected in operative relationship with feed dog 22, preferably of the four motion type, to which there is thereby imparted a rising and falling movement. The operation of such a feed dog, and suitable mechanism for imparting rising and falling movements thereto, are described in Kucera Patent 2,199,666, issued May 7, 1940.

Shaft 15 also carries a second eccentric 25 which cooperates with strap portion of pitman or link 26 which, through suitable connections of the type disclosed in said Kucera patent, serve to axially reciprocate rock shaft 28 (Fig. 5) which carries at its end one or more loopers 30. These loopers are thus given their needle avoid movement. The end of shaft 15 also carries ball stud 32 cooperating with a pitman or compound link 33, the lower end of which is connected with rock shaft 28 by means of a crank arm 34. Rock shaft 28 is thus oscillated, thereby imparting loop-taking and shedding movements to the loopers 30. This mechanism need not be described in detail here since it will be found fully described in Kucera Patents Nos. 2,172,321 and 2,199,666.

Shaft 15 is provided with a crank portion 36 (Fig. 4) extending between the counterweights 37 formed integral therewith or secured in some other manner to adjacent portions of the shaft. Pitman 38 cooperating with the crank 36 is pivotally connected at its opposite end by pin 39 with the downwardly extending arm of bell crank lever 40 rockably mounted upon the sewing machine frame by means of the shaft 41. This shaft is journaled in bushings 42 and 43 (Fig. 2) carried by the needle head portion of the frame.

The outer end of the forwardly extending arm of bell crank lever 40 is connected by link 44 through pivot 45 with block 46 secured to needle bar 47. This needle bar is mounted for vertical reciprocation in the needle head in a manner well known in the art. Also mounted for vertical reciprocation in the needle head is the presser bar 49 carrying at its lower end presser foot 50 (Figs.

1 and 5), in a manner to be explained more fully hereinafter. The presser bar 49 is urged downwardly by means of a spring arrangement 51 of any suitable form. For the purpose of lifting the presser foot against the action of the spring there is provided block 52 (Fig. 4) secured to the presser bar, which block is adapted to be engaged by finger 53 secured to rock shaft 54. An arm 55 is also secured to the rock shaft and is connected by link 56 with an upward extension of lever 58 secured to rock shaft 59, which rock shaft is mounted on a portion of the sewing machine frame. The other end of the lever 58 is connected by chain 60 with a foot treadle or any other convenient control member (not shown) operable at will by the machine operator.

Referring to the elements comprising the material feeding mechanism which are above the work support, and which cooperate with the feed dog 22 which engages the under side of the fabric, reference should be made to Figs. 3, 5, 6 and 7, and to the detail views, Figs. 8 to 15 inclusive. The needle bar 47 in the illustrative machine carries two needles 62 and 63, which are reciprocated by means of the needle bar. These needles pass through the needle openings 65 and 66 in the presser foot 50, thereby permitting stitching of the fabric.

Both presser foot 50 and the feed roller 68, of a novel and improved construction as described below, are mounted on a rock frame 70. The rock frame is pivoted at 71 to a shank portion 72 which, in turn, is secured to the presser bar 49.

The rock frame 70, at that portion thereof extending in front of the pivot 71, is formed with the two spaced arms 74. Presser foot 50 is retained between the arms 74 by means of pivot screws 75, which are located in a line intersecting the middle of the needle bar axis, which is substantially midway between needles 62, 63 and also midway between the needle openings 65, 66. Rock frame 70 projects in rear of the pivotal support 71 in the form of a yoke 77. The feed roller 68 is located between the arms of the yoke and is mounted on shaft 78 fastened in the rock frame. Sleeve 80, the lower end of which is rounded and provided with tip portion 81, is seated in a recess and aperture 83 in the end of the yoke member 77. Rod 84, provided with an enlarged threaded portion 85 which is adjustably mounted in a threaded opening in the arm 86 and locked in place by nut 87, extends into the sleeve 80. Surrounding the rod 84 is a helical compression spring 89, which bears against the threaded portion 85 of the telescoping rod.

The arm 86, which supports the rod 84, forms part of a bracket that has a portion 90 extending through a guide opening 91 in the needle head. This bracket is secured to collar 92 on presser bar 49 by means of screw 93. It serves both to support the rod 84, and to prevent the presser bar 49 from turning or oscillating about its axis.

Spring 89 forces the sleeve 80 downwardly into contact with the rock frame 70 at a point well in the rear of the shaft 78 for the feed roller 68, and also well in the rear of the pivotal support 71 for the rock frame 70. This spring therefore exerts a pressure on the rock frame which results in adding to the pressure of the spring 51 on the presser bar 49 by which the feed roller 68 is forced downwardly, and it also acts to decrease the pressure exerted by spring 51 on presser foot 50. The tension of the helical spring 89 is, of course, less than the tension of the leaf spring 51 bearing on the presser bar 49, but the net result of the ar-

rangement is that the presser foot is forced against the fabric with a comparatively light pressure, while the feed roller 68 is pressed against the fabric with a much stronger pressure.

On the rearward portion of the rock frame 70, and extending upwardly and projecting rearwardly therefrom, is a lug 95, which extends between the lower end of a pair of lower guide bars 96 and 97 (Figs. 1 and 5). This serves to steady the rock frame, and prevents turning movements of the latter about or with the presser bar, while permitting the rock frame 70 to oscillate freely on the pivotal supports 71 and 75 when the feed roller 68 and presser foot 50 are in engagement with the fabric. A U-shaped wire 99 secured to the lower ends of guide bars 96 and 97 underlies the lug 95 and limits the downward movement of rock frame 70 and feed roller 68 carried thereby.

The feed roller 68 is intermittently rotated by means of a clutch spring 100 (Figs. 8 to 11) having a tapered frusto-conical inner surface and a straight cylindrical outside surface which engages the inner surface of the feed roller. The provision of the taper on the inner surface of the spring serves to exert a positive and instantaneous, flexible gripping action at its driving end 101, while the driven end 102 is of heavier construction for more positive action in its continuous cooperation with the driving lever 103.

Bent lug 104 extending from the driven end of spring 100 engages a slot 105 in the outer rim portion of the driving lever 103 (Figs. 12 and 13). As the driving lever 103 is rocked toward the needles 62, 63, there is a tendency to expand the spring so that the outside surface of the spring 100 will grip the inner surface of the feed roller 68 and cause the roller to rotate so as to feed the work over the work arm 13. As the lever rocks in the opposite direction the spring 100 tends to contract, rather than expand, so that it turns readily within the roller and the roller remains stationary. To keep the feed roller 68 at rest during this reverse non-feeding movement of the lever and spring, a ball 106 (Fig. 14), which is normally yieldingly held against the side face of the feed roller 68, is wedged against the frame so as to prevent retrograde movement of the feed roller. This ball braking means is urged against the side of the feed roller 68 in an inclined passage in the rock frame 70 by a plunger 107, which is spring-urged by flat spring 1070. During feed movements of the feed roller the ball 106 is urged upwardly (Fig. 14) out of wedging relation.

Driving lever 103, driving the feed roller 68, is operated from vertical rock shaft 108 (Figs. 3 and 7) by mechanism which includes ball stud assembly 109 having a threaded portion which is screwed into the upper end of the driving lever 103 and secured in place thereon by nut 110. Ball stud assembly 109 has attached thereto a horizontal link 111 (Fig. 15) which is of yielding construction and is held in place by a clamp screw 112. Horizontal link 111 is also connected with a second similar ball and stud assembly 113, which is fastened by means of a nut 114 (Fig. 3) to a downwardly extending lug portion of a split collar 115 which is secured to the lower end of the vertical rock shaft 108 by means of a clamping screw 116. The rock shaft 108 is carried by bracket 117 secured to the side of the frame by means of screws 118.

At its upper end the vertical rock shaft 108 has an enlarged head portion 119 of forked or 75 split construction, which has a threaded hole for

the reception of the micrometer adjustment ball screw stud 120 which is clamped in adjusted position in the slotted upper end of the rock shaft by means of a screw 121. By varying the position of the ball screw stud 129 in relation to the axis of the vertical rock shaft 108, the effective length of the lever arm formed by the ball screw stud 120 is varied, and this regulates the stroke or length of each feeding movement of the feed roller 68. Ball screw stud 120 receives its movement by means of pitman strap 122 (Fig. 3) which with a cap member 122 secured by screws 122a embraces at one end the ball portion of ball screw stud 120, and at the other end embraces ball eccentric 124 on the main shaft 15, adjacent combined hand wheel and pulley 14.

The alternate feed roller and presser foot arrangement shown in Figs. 16 to 18 is somewhat simpler than the embodiment described above and has certain advantages under specific circumstances. The feeding action of the feed roller is affected to a lesser extent by variations in the seam thicknesses.

The modified construction is, in general, similar to the construction above described, except that the feed roller 68', driving lever 103', and ball braking means 106' which prevents retrograde movement of the feed roller, are all mounted directly on the shank portion 72' secured to the lower end of the presser bar 49'. Presser foot 50' is retained between the arms 74' of rock frame 70' by pivot screws 75', as in the construction described above. Rock frame 70' is also formed with rearwardly projecting yoke portion 77', provided with recess and aperture 83' in which one end of the helical spring 89' is engaged. But this spring is a tension spring, not a compression spring as in the first modification, and is arranged to pull the rock frame 70' upwardly at the yoked end 77' thereof, thus applying a downward pressure to the presser foot 50' which bears against the feed dog 22'. The normal downward pressure exerted by the presser bar 49' under the action of its spring is exerted only on the feed roller 68'.

The feed roller 68' is mounted on shaft 73' carried by the shank 72' and which extends beyond the latter to provide a pivotal support for the rock frame 70'. It is driven by means of driving lever 103' and a tapered spring clutch positioned within the roller, the driving mechanism being identical with that above described. Ball bearing means 106' is mounted directly on the shank 72', and comprises ball 106' which is urged inwardly in an aperture in the shank against the face or side of feed roller 68' under the action of plunger 107' and flat spring 108'. This braking means functions in the same way as in the embodiment described above to prevent retrograde motion of feed roller 68' during return or backward movement of the driving lever 103' by wedging between the shank 72' and the face of roller 68'.

As shown, shank 72' is provided with a rearward extension or lug 950' which extends between the lower ends of the guide bars 96' and 97', and is held against movement below these guide bars by a U-shaped wire, as in the construction described above. The guide bars 96' and 97' are secured to the frame of the sewing machine, exactly as shown in Fig. 3 which illustrates the first modification.

The operation of our new and improved feed roller 68, cooperating with the feed dog 22 to move material with reference to the stitch-

forming instrumentalities, as well as the operation of the other mechanism associated therewith and forming part of our invention, will be apparent from the foregoing description.

5 Feed roller 68 is operated from pitman 123, which causes rock shaft 108 to oscillate, thereby imparting rotary motion to the feed roller through driving lever 103 which is in operative relationship with tapered spring clutch 100. The 10 ball braking means 106 prevents movement of the feed roller in the opposite direction when the driving lever 103 makes its return movement. In this way the feed roller is driven only in one direction. It is held with a firm pressure against 15 the material being sewed.

In the first modification illustrated in Figs. 1 to 7, the pressure of the leaf spring 51 is increased by the additional pressure provided by helical compression spring 89 acting on the feed roller 20 to urge the latter against the work. The arrangement is such that the presser foot 50 is pressed against the material with lessened pressure, due to the lifting action of spring 89 thereon. This presser foot is arranged so that it 25 may rock due to the passage beneath it of cross seams in the fabric, without interfering with stitching by the needles 62, 63, which pass through apertures 65, 66 in the presser foot. It 30 will be appreciated that the strong downward pressure applied to the feed roller 68 assists in the movement of heavy materials and materials which are difficult to feed across the work arm of the sewing machine, these materials, at the same time, being advanced by the co-action of 35 the presser foot 50 and the feed dog 22.

In the second or modified form of the invention, illustrated in Figs. 16 to 18, the feed roller 68' is forced downward by means of the pressure exerted by leaf spring 51 on presser bar 49', while the presser foot 50' is urged against the feed dog 22' by the upward tension exerted by helical tension spring 89'.

The length of the feeding movement imparted to the feed roller 68, and thus the length of the stitch, is regulated as above described by adjusting the position of the ball screw stud 129 in relation to the axis of the rock shaft 108 by means of the micrometer adjustment means afforded by the screw threads. The operation of the other parts of the sewing machine will be apparent from the foregoing detailed description.

While several illustrative forms of the invention have been disclosed in considerable detail, 55 it should be understood that numerous changes may be made in the construction and arrangement of the various parts without departing from the general principles and scope of the invention.

We claim:

1. In a sewing machine including a main drive shaft, a work arm over which material is fed past stitch-forming instrumentalities, and feed mechanism for said material comprising a presser bar mounted for movement toward and away from said work arm and a feed roller journaled at the lower end of said presser bar and adapted to engage the material on said work arm for feeding the same thereon, the improvement which comprises means for driving said feed roller from said main drive shaft comprising one-way clutch means within said feed roller, an eccentric on said main drive shaft, a pitman actuated thereby, a vertical rock shaft adjacent said presser bar connected with said pit-

man for oscillation thereby about the axis of said shaft, and a driving lever actuated by the rocking of said rock shaft, said driving lever being operatively connected to said clutch, whereby said feed roller is intermittently rotated in one direction.

2. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said presser bar and adapted to engage the material on said work arm for feeding the same thereon, the improvement which comprises means for driving said feed roller from said main drive shaft comprising, clutch means within said feed roller, an eccentric on said main drive shaft, a pitman actuated thereby, a vertical rock shaft adjacent said presser bar connected with said pitman for oscillation thereby about the axis of said shaft, a driving lever actuated by the rocking of said rock shaft, said driving lever being operatively connected to said clutch, whereby said feed roller is intermittently rotated in one direction upon movement of said driving lever in one direction, and stop means directly engaging said feed roller for preventing rotation of said feed roller in the reverse direction upon movement of said driving lever in the reverse direction.

3. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said presser bar and adapted to engage the material on said work arm for feeding the same thereon, the improvement which comprises means for driving said feed roller from said main drive shaft comprising, clutch means within said feed roller, an eccentric on said main drive shaft, a pitman actuated thereby, a vertical rock shaft adjacent said presser bar connected with said pitman for oscillation thereby about the axis of said shaft, a driving lever actuated by the rocking of said rock shaft, and ball means in contact with said feed roller so positioned with respect thereto as to allow said roller to rotate in one direction, but adapted to wedge and prevent rotation of said feed roller in the reverse direction, said driving lever being operatively connected to said clutch whereby said feed roller is intermittently rotated in one direction upon movement of said driving lever in one direction, said feed roller being held by said ball means from rotating in the reverse direction upon the return movement of said driving lever.

4. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said presser bar and adapted to engage the material on said work arm for feeding the same thereon, the improvement which comprises means for driving said feed roller from said main drive shaft, said means including a tapered spring clutch, flexible at its driving end and relatively more rigid at its driven end, positioned within said feed roller, a driving lever, and an eccentric on said main drive shaft, for oscillating said lever, one end of said driving lever being

operatively connected to said driven end of said tapered spring clutch, thereby actuating said clutch, whereby, upon movement of said driving lever in one direction, the driving end of said clutch is forced into contact with the interior of said feed roller, thereby causing said roller to rotate and feed material across said work arm.

5. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said presser bar and adapted to engage the material on said work arm for feeding the same thereon, the improvement which comprises means for driving said feed roller from said main drive shaft, said means including a tapered spring clutch, flexible at its driving end and relatively more rigid at its driven end, positioned within said feed roller, stop means in direct contact with said feed roller for preventing rotation of said roller in the reverse direction, a driving lever, and an eccentric on said main drive shaft for oscillating said lever, one end of said driving lever being operatively connected to said driven end of said tapered spring clutch, thereby actuating said clutch, whereby, upon movement of said driving lever in one direction, the driven end of said clutch is forced into contact with the interior of said feed roller, thereby causing said roller to rotate and feed material across said work arm, said feed roller being held by said stop means against reverse rotation upon the return movement of said driving lever.

6. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said presser bar and adapted to engage the material on said work arm for feeding the same thereon the improvement which comprises means for driving said feed roller from said main drive shaft, said means including a tapered spring clutch positioned within said roller, said spring clutch being flexible at its driving end and relatively more rigid at its driven end, ball means associated with said feed roller for permitting rotation of said feed roller in one direction, but acting as braking means to prevent rotation of said feed roller in the reverse direction, a driving lever, and an eccentric on said main drive shaft for oscillating said lever, one end of said driving lever being operatively connected to said driven end of said tapered spring clutch, thereby actuating said clutch, whereby, upon movement of said driving lever in one direction, the driven end of said clutch is forced into contact with the interior of said feed roller to cause said roller to rotate and feed material across said work arm, said feed roller being held by said ball braking means against rotation in the reverse direction upon return movement of said driving lever.

7. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said presser bar and adapted to engage the material on said work arm for feeding the same thereon, the improvement which com-

prises means for driving said feed roller from said main drive shaft comprising, a tapered spring clutch, flexible at its driving end and relatively more rigid at its driven end, positioned within said feed roller, an eccentric on said main drive shaft, a pitman actuated thereby, a vertical rock shaft connected with said pitman and rocked thereby, and a driving lever oscillated by the rocking of said rock shaft, said driving lever being operatively connected to said tapered spring clutch at its driven end and serving, upon movement of said driving lever in one direction, to force the driving end of said clutch into contact with the interior of said feed roller, whereby said roller is caused to rotate and feed material across said work arm.

8. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said presser bar and adapted to engage the material on said work arm for feeding the same thereon, the improvement which comprises means for driving said feed roller from said main drive shaft comprising, a tapered spring clutch, flexible at its driving end and relatively more rigid at its driven end, positioned within said feed roller, stop means directly engaging said feed roller to permit rotation in one direction and prevent said feed roller from rotating in the reverse direction, an eccentric on said main drive shaft, a pitman actuated thereby, a vertical rock shaft actuated by said pitman, and a driving lever oscillated by the rocking of said rock shaft, said driving lever being operatively connected to said tapered spring clutch at its driven end and serving, upon movement of said driving lever in one direction, to force the driving end of said clutch into contact with the interior of said feed roller, whereby said roller is caused to rotate and feed material across said work arm, movement of said feed roller in the reverse direction during the return movement of said driving lever being prevented by said stop means.

9. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said pressure bar and adapted to engage the material on said work arm for feeding the same thereon, the improvement which comprises means for driving said feed roller from said main drive shaft comprising, a tapered spring clutch, flexible at its driving end and relatively more rigid at its driven end, positioned within said feed roller, ball means in contact with said feed roller so positioned with respect thereto as to allow said roller to rotate in one direction, but adapted to wedge and prevent rotation of said feed roller in the reverse direction, an eccentric on said main drive shaft, a pitman actuated thereby, a vertical rock shaft actuated by said pitman, and a driving lever oscillated by said rock shaft, said driving lever being operatively connected to said tapered spring clutch at its driven end and serving, upon movement of said driving lever in one direction, to force the driving end of said clutch into contact with the interior of said feed roller, whereby said roller is caused to rotate and feed material across said work arm, movement of said feed roller in the reverse direction

during the return movement of said driving lever being prevented by wedging of said ball means.

10. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said presser bar and adapted to engage the material on said work arm for feeding the same thereon, the improvement which comprises means for driving said feed roller from said main drive shaft and for regulating the extent of rotation of said roller and thus the length of the stitch, said means comprising, one-way clutch means positioned within said feed roller, an eccentric on said main drive shaft, a pitman actuated thereby, a vertical rock shaft adjacent said presser bar arranged to be rocked by said pitman, and a driving lever for driving said clutch and said feed roller upon the rocking of said rock shaft, said pitman being connected to one end of said vertical rock shaft by screw means capable of micrometer adjustment by which the extent of movement of said rock shaft may be regulated, thereby regulating the extent of the rotation imparted to said feed roller and the length of the stitch.

11. In a sewing machine including a main drive shaft, a work arm over which material is fed past stitch-forming instrumentalities, and feed mechanism for said material comprising a feed roller adapted to engage the material on said work arm for feeding the same thereon, the improvement which comprises means for driving said feed roller from said main drive shaft and for regulating the extent of rotation of said roller and thus the length of the stitch, said means comprising, an eccentric on said main drive shaft, a pitman actuated thereby, a vertical rock shaft having one end adjacent said feed roller and arranged to be rocked by said pitman, and a driving lever for driving said feed roller from said rock shaft, said pitman being connected to one end of said vertical rock shaft by screw means capable of micrometer adjustment by which the extent of movement of said rock shaft may be regulated, thereby regulating the extent of the rotation imparted to said feed roller and the length of the stitch.

12. In a sewing machine including a main drive shaft, a work arm over which material is fed past stitch-forming instrumentalities, and feed mechanism for said material comprising a presser bar mounted for movement toward and away from said work arm and a feed roller journalled at the lower end of said presser bar and adapted to engage the material on said work arm for feeding the same thereon the improvement which comprises means for driving said feed roller from said main drive shaft and for regulating the extent of rotation of said roller and thus the length of the stitch, said means comprising, a tapered spring clutch, flexible at its driving end and relatively more rigid at its driven end, positioned within said feed roller, an eccentric on said main drive shaft, a pitman actuated thereby, a vertical rock shaft adjacent said presser bar arranged to be rocked by said pitman, and a driving lever operatively connected to said rock shaft and to the driven end of said tapered spring clutch, whereby, upon rocking of said rock shaft and the resulting movement of said driving lever in one direction, the driving end of said clutch is forced into contact with the interior of said feed roller, thereby

causing said roller to rotate and feed material across said work arm, said pitman being connected to one end of said vertical rock shaft by screw means providing a micrometer adjustment by which the extent of movement of said rock shaft may be regulated, thereby regulating the extent of the rotation imparted to said feed roller and the length of the stitch.

13. In a sewing machine including a main drive shaft, a work arm over which material is fed past stitch-forming instrumentalities, and feed mechanism for said material comprising a presser bar mounted for movement toward and away from said work arm and a feed roller journaled at the lower end of said presser bar and adapted to engage the material on said work arm for feeding the same thereon, the improvement which comprises means for driving said feed roller from said main drive shaft and for regulating the extent of rotation of said roller and thus the length of the stitch, said means comprising, a tapered spring clutch, flexible at its driving end and relatively more rigid at its driven end, positioned within said feed roller, ball means associated with said feed roller which permits rotation of said roller in one direction, but which wedges and thus prevents rotation of said roller in the reverse direction, an eccentric on said main drive shaft, a pitman actuated thereby, a vertical rock shaft actuated by said pitman, and an oscillatory driving lever operatively connected to said rock shaft and to the driven end of said tapered spring clutch, whereby, upon movement of said driving lever in one direction, the driving end of said clutch is forced into contact with the interior of said feed roller, thereby causing said roller to rotate and feed material across said work arm, said feed roller being prevented by wedging of said ball means from rotating in the reverse direction during the return movement of said driving lever, said pitman being connected to one end of said vertical rock shaft by micrometer adjustment means by which the extent of movement of said rock

shaft may be regulated, thereby regulating the extent of the rotation imparted to said feed roller and the length of the stitch.

14. In a sewing machine including a main drive shaft, a work arm over which material is fed past stitch-forming instrumentalities, a presser bar mounted for movement toward and away from said work arm, a rock frame secured to one end of said presser bar, a presser foot pivotally secured to said rock frame, and a feed roller for feeding material across said work arm journaled in said rock frame, the improvement which comprises a tapered spring clutch positioned within said feed roller, means including a vertical rock shaft arranged to be rocked by an eccentric on said main drive shaft and an oscillating driving lever actuated by the rocking movements of said rock shaft for driving said feed roller in one direction through said tapered spring clutch from said main drive shaft, means for preventing rotation of said feed roller in the reverse direction, spring means acting on said rock frame for yieldably urging said feed roller against said work arm, and spring means acting on said rock frame in a reverse direction from said first named spring means for urging said presser foot against said work arm.

Certificate of Correction

Patent No. 2,494,888

January 17, 1950

HAROLD J. LE VESCONTE ET AL.

It is hereby certified that error appears in the printed specification of the above numbered patent requiring correction as follows:

Column 9, line 45, for the word "pressure" read *presser*;
and that the said Letters Patent should be read with this correction therein that the same may conform to the record of the case in the Patent Office.

Signed and sealed this 30th day of May, A. D. 1950.
